J. H., J. F., AND F. J. PUKE.
KNIFE POUCH.
APPLICATION FILED SEPT. 4, 1920.

Patented Oct. 10, 1922.

UNITED STATES PATENT OFFICE.

JOSEPH H. PUKE, JOHN F. PUKE, AND FERDINAND J. PUKE, OF CINCINNATI, OHIO.

KNIFE POUCH.

Application filed September 4, 1920. Serial No. 408,146.

To all whom it may concern:

Be it known that we, JOSEPH H. PUKE, JOHN F. PUKE, and FERDINAND J. PUKE, citizens of the United States of America, and 5 residents of Cincinnati, in the county of Hamilton and State of Ohio, have invented a new and useful Improvement in a Knife Pouch, of which the following is a specification.

10 An object of our invention is to provide a knife pouch, for use especially by butchers, that can be thoroughly cleaned.

Another object is to provide a pouch that will not absorb water, and which will not 15 afford lodgment in any way to germs or filth, but that such germs and filth will be accessible of proper cleaning utensils and disinfecting agents, without injuring the pouch.

20 These and other objects are attained by the means described herein and disclosed in the accompanying drawing in which:

Fig. 1 is a fragmental elevation, parts being broken away of a pouch embodying our 25 invention.

Fig. 2 is a sectional view, on reduced scale, taken on line 2—2 of Fig. 1.

Fig. 3 is an enlarged fragmental view of parts shown in Fig. 2.

30 Our invention comprises a knife pouch A that can be carried upon the butcher's belt, such pouch being adapted to be opened and the inside exposed in such manner that it can be cleaned by means of a brush, scraper or any other suitable instrument.

The pouch A has a back a, preferably made of waterproof leather, in the upper end of which are a series of slots a' through which the butcher's belt can be passed to 40 support the pouch. Any other suitable attachment means may be provided. Upon the lower end of the back a is mounted a rear frame b. The rear frame is made preferably of hard rubber or fiber and may 45 be attached to the back a in any manner desired, such as by means of a thin strip of fiber or rubber b' forming a moulding and the screws c extending through such moulding and back a and securing same to the frame b. A lug b² is formed upon the bottom of the frame b and forms a hinge member. A catch b³ extends from the frame near its top. A forward frame d has the lugs d' that form complementary hinge 50 members, the pins d² pivotally connecting the lugs b² and d'. The forward frame has

a front or cover e of material similar to the back a, such cover being secured upon the forward frame in any manner desired, for example, in the same manner in which the 60 rear frame and back a are attached. A slot d³ is formed through the forward frame, cover e and front moulding d⁵, in such position that the catch b³ will engage therein, the shoulder b⁴ on the catch engaging the 65 shoulder d⁴ formed interiorly to the slot and thereby securing the frames upon one another in a normal or closed position. The adjacent edges of the two frames are preferably tongued and grooved in such manner 70 that the frames will seat firmly upon one another in the closed position of the pouch. A knife edge and point protector or buffer strip f, preferably of rubber, is secured upon one of the frames, at the bottom thereof, in 75 such wise that the protector will extend over the bottom of both frames. This buffer may be made in one piece that can be removably attached to the one frame, it may be fixed upon one frame, or it may be made in two 80 sections, one section being attached to each of the forward and rear frames. A one piece protector is preferable.

The heads of the screws seat in counter-sunk holes in the mouldings, and the catch 85 b³ although it can be readily manipulated by means of the fingernails, does not protrude or extend from the slot d³, thereby avoiding any contact between the edge of the butcher's knife and any metal that would 90 injure such edge.

The pouch is mounted on the butcher's belt g and may have one or more compartments h in each of which a knife may be carried. Health regulations of the Department of Agriculture require that whenever a butcher comes upon an abscess in any animal, or if the animal be diseased, that the butcher clean his hands, knife and knife pouch. The natural thing for a butcher to 100 do under such circumstances, is to insert his knife in the pouch and then wash his hands. The pus and disease germs are smeared upon the pouch and some of these germs and pus will reach inaccessible parts of the pouch 105 and will find lodgment in the pores and amongst the fibers of the material of which the pouch is made. Up to this time pouches have been generally made of wood and soft leather. The butcher then rinses his knife 110 and pouch in an antiseptic solution. To secure actual disinfection the pouch should

be thoroughly cleaned. To clean the applicants' device, the butcher releases the engagement of the catches upon the shoulders ⁴ and opens the pouch and then by means ⁵ of a scrubbing brush or other suitable instrument and a sterilizing solution, the surface of the entire pouch, both inside and outside can be thoroughly cleaned and disinfected. The disease germs cannot find ¹⁰ lodgment in either waterproofed leather or hard rubber or fiber; the germs will stay on the surface of the pouch and the disinfectant will kill them. The complementary frames are adapted when closed, to provide ¹⁵ a pouch that is leak proof along the sides and bottom, and which is open at the top for the reception of knives.

What we claim is:—

1. In a knife pouch the combination of a substantially U shaped rear frame, a forward frame complementary to the rear frame, hinge members extending downwardly below the frames, pivots connecting the hinge members, the frames bearing such relation that they may engage to form a case having closed and leak proof sides and bottom, and the hinge members being so formed that the hinge is disposed below the closed bottom of the case.
2. In a butcher's knife pouch the combination of a back, a rear frame of a substantially U shape mounted on the back, a forward frame of a shape complementary to the rear frame, a front mounted on the forward frame, the front and forward frames having slots therein, shoulders formed on the forward frame disposed within the slots, spring catches mounted on the rear frame adapted to enter the slots in the front and forward frames, to have their forward ends contained wholly within said slots and to engage the shoulders, hinge members extending downwardly from the frames, pivots connecting the hinge members about which the frames may be rotatably actuated whereby the frames may be brought into engagement along their bottoms and branches to form a compartment closed and leak proof along its bottom and sides, the spring arms being adapted to engage the shoulders and to yieldingly retain the frames in said relation.
3. A butcher's knife pouch composed of two complemental hingedly mounted sections, said sections being adapted to assume an extended and a contracted relation and being provided with means along their

side edges and bottom whereby when the sections are in their contracted or closed relation, said means are held in engagement ⁶⁰ whereby a leak proof joint is formed, along the sides and bottom of the pouch, and an aperture is provided at the top of the pouch for the reception of knives.

4. A butcher's knife pouch composed of two complemental hingedly mounted sections, said sections being adapted to assume an extended and a contracted relation and being provided with means along their side edges and bottom whereby when the sections ⁷⁰ are in their contracted or closed relation, said means are held in engagement whereby a leak proof joint is formed along the sides and bottom of the pouch, and an aperture is provided at the top of the pouch for the ⁷⁵ reception of knives, and means to secure the sections in a closed relation.

5. A butcher's knife pouch composed of two complemental sections, said sections being provided with hinges at one end and ⁸⁰ open at the opposite end for the reception of knives, said sections being provided with means along their side and bottom edges whereby when the sections are closed, a leak proof joint is formed along the sides and ⁸⁵ bottom of the pouch.

6. A butcher's knife pouch composed of two complemental sections, said sections being provided with hinges at one end and open at the opposite end for the reception ⁹⁰ of knives, said sections being provided with means along their side and bottom edges whereby when the sections are closed, a leak proof joint is formed along the sides and ⁹⁵ bottom of the pouch, and means to hold the sections in a closed relation.

7. A butcher's knife pouch composed of two complemental sections, said sections being provided with hinges at one end and open at the opposite end for the reception ¹⁰⁰ of knives, said sections being provided with means along their side and bottom edges whereby when the sections are closed, a leak proof joint is formed along the sides and ¹⁰⁵ bottom of the pouch, and a knife protector adapted to lie within the pouch adjacent the bottom thereof.

In testimony whereof, we have hereunto subscribed our names this 2nd day of September, 1920.

JOSEPH H. PUKE.
JOHN F. PUKE.
FERDINAND J. PUKE.
